**COMBINED FOOTREST AND SHOE HEEL
PROTECTOR FOR USE BY AN AUTOMO-
BILE DRIVER**

Hardin Lee Ward, Sr., 3215 Pine St.,
Dallas, Tex. 75215

Filed Aug. 19, 1965, Ser. No. 86,699

Term of patent 14 years

(Cl. D14—6)

FIG. 1

FIG. 2

FIG. 4

FIG. 3

FIG. 5

FIG. 6

FIGURE 1 is a perspective view of a combined footrest and shoe heel protector for use by an automobile driver.

FIGURE 2 is a plan view thereof on a reduced scale.

FIGURE 3 is a front elevational view of the combined footrest and shoe heel protector shown in FIGURE 2.

FIGURE 4 is a side elevational view thereof taken from the right in FIGURE 1.

FIGURE 5 is a view in side elevation as seen from the left in FIGURE 1; and

FIGURE 6 is a bottom view thereof.

I claim:

The ornamental design for a combined footrest and shoe heel protector for use by an automobile driver, as shown.
